UNITED STATES PATENT OFFICE.

HARVEY HUBBELL, JR., OF BRIDGEPORT, CONNECTICUT, ASSIGNOR TO HARVEY HUBBELL, INCORPORATED, OF BRIDGEPORT, CONNECTICUT, A CORPORATION OF CONNECTICUT.

CAP AND SHELL FASTENING.

Application filed May 7, 1927. Serial No. 189,649.

This invention relates to shells for electrical devices such as are used for lamp sockets, depending switches and the like, and has as its particular object to provide an improved fastening means for securing the body section and the cap section of the shell together.

One of the objects of the invention is to provide a fastening means for the cap and shell section which will more securely secure these elements together than do the fastenings now generally employed, and therefore, where the shell is used to carry a weight, such as glass shades or globes, will be more reliable and will be much less liable to separate under the weight of the shade or globe and permit it to drop.

It is also an object of the invention to provide a securing means for this type of devices in which the cap and shell may be more easily separated when desired than can the devices now generally used.

With the foregoing and other objects in view I have devised the construction illustrated in the accompanying drawing embodying the preferred form of my invention.

In this drawing,

Fig. 1 is a side elevation of the lamp socket shell with parts broken away to more clearly show the construction.

Fig. 2 is a transverse section substantially on line 2—2 of Fig. 1.

Fig. 3 is a bottom plan view of the cap.

Fig. 4 is a side elevation of the cap showing the locking ring in section.

Fig. 5 is a transverse section of one side of the cap substantially on line 5—5 of Fig. 3 showing its position on the shell, the upper portion of the shell being also shown in section and the parts being shown in the position they occupy when the securing means is released.

Fig. 6 is a similar detail section, the section of the cap being substantially on line 6—6 of Fig. 3.

Fig. 7 is a detail section substantially on line 7—7 of Fig. 4 on an enlarged scale.

Fig. 8 is a front elevation of the structure shown in Fig. 7.

Fig. 9 is a vertical section of this structure.

Fig. 10 is an elevation of the upper or inner end of a section of the shell on an enlarged scale, and

Fig. 11 is a detail section of this end of the shell.

I have shown my invention in the drawing as applied to a sheet metal shell for an electric pull socket, but it is, of course, not limited to this type of socket as it is equally adapted for use with a key socket, keyless socket, depending switches and so forth. The enclosing shell shown comprises the usual shell or body section 12 and the cap section 13 enclosing the works of the socket not shown in detail in the present construction as they of themselves form no part of my invention. The shell section 12 has the usual notch 14 leading from its upper or inner end for the guide 15 of the pull chain 16 for operating the switch, not shown, and the shell 12 has the usual threads 17 to which any desired type of shade holder may be attached. Both the cap and the shell are lined with the usual fibre insulation 18 and 19.

The shell 12 is provided a suitable distance 20 from its upper end with a row of openings 20. It is preferred that these openings be substantially rectangular and that they be equally spaced throughout the periphery of the shell and also equally spaced from the end of the shell. The cap 13 is provided with a plurality of tongues 21 which are formed by slitting the cap inwardly from its free edge a suitable distance as shown at 22. I prefer to provide four or five of these tongues 21 equally spaced about the cap as this number has proven very satisfactory in practice. Of course, I do not wish to be limited to this particular number because it will be obvious the number may be changed if found desirable. 90 Each tongue is provided with an inwardly projecting nib or lug 23. This nib or lug may be conveniently formed by slitting the wall of the tongue transversely as indicated at 24, and then forcing the metal inwardly at the lower side of this slit. If the slit is curved upwardly somewhat as shown in Fig. 8, then when the wall is forced inwardly the upper edge of this nib will be substantially straight as shown in Fig. 9. If the curve is made of 100 a smaller radius than the center of the nib may be somewhat higher than its ends giving it a sort of hook effect if desired, but it is preferred to have it substantially straight. The cap is provided at a suitable distance from its free edge with a shoulder 25, and the nibs 23 are spaced from this shoulder a distance corresponding to the distance of the openings 20 in the shell from the end of this shell, so that when the end of the shell is 110

inserted in the cap its movement is limited by engagement of the end of the shell with this shoulder and at the proper position so that the nibs or lugs 23 may extend into these 5 openings.

Mounted on the outside of the cap and in position to slide longitudinally on this cap is a locking ring 26. This ring is preferably of sheet metal similar to that of which the shell 10 and the cap are constructed, and has an inwardly extending flange 27 at one end to engage the outer portion of the shoulder 25, which, therefore, limits its movement in one direction. At its other end it is formed with 15 a bead 28 projecting inwardly on its inner wall. The cap is provided with outwardly extending lugs 29 a short distance below the shoulder 25 and on the portions of its side walls between the tongues 21, and which co-operates with the bead 28, as shown in Fig. 6, to limit the upward movement of the ring. In manufacturing, the cap and ring yield sufficient so that the ring may be forced over the 25 lugs to the proper position. Two of these portions on opposite sides of the cap are also provided with inwardly extending lugs 36 having upright side walls to engage side walls of any of the openings 20 in the shell to prevent turning of the cap on the shell.

30 The metal of which the cap is constructed is resilient and the tongues 21 are so formed that they tend to move outwardly sufficiently so that the inner tip of the nibs 23 just clear the outer surface of the shell, as indicated in Fig. 5, when the ring 26 is in the upper position as indicated in Figs. 4, 5 and 6. The ring, however, is of such a diameter that when it is forced to its lower position with the flange 27 against the outer wall of the shoulder 25, as indicated in Fig. 1, it will force the free ends of the tongues 21 inwardly and cause the nibs or lugs 23 to project into the openings 20 in the shell opposite which they happen to be located, as indicated in Figs. 1 and 2. The tongues 21 and also the free edge of the cap are provided with beads 30 and 31 over which the bead 28 on the ring passes, and thus these beads cooperate to yieldably lock the ring in the securing position of Fig. 1. 45 It will be obvious that by forcing the ring 26 upwardly from the position of Fig. 1 the tongues will be released permitting them to move outwardly and carry their lugs or nibs 23 free of the openings 20 in the shell.

50 The free edge portion of the body of the shell 12 may be more or less corrugated as indicated, especially between the openings 20 and the free edge of the shell, although these corrugations are not absolutely necessary. 60 When they are used the grooves of the corrugations are arranged in alignment with the openings 20 and thus form a guiding means to guide the nibs 23 to the openings 20 when the shell and the cap are placed in telescoping relation. Also the free edge of the shell 65

may be rolled inwardly or rounded somewhat as shown at 32, in Fig. 11, so that the operation of inserting the end of the shell in the cap may be facilitated. This rolling over of the edge also rounds over the ends of the ribs 34 70 of the corrugations at the edge of the shell as indicated at 33, Fig. 10, so that when the end of the shell is inserted in the cap, if the nibs 23 happen to be in alignment with the ribs and corrugations they will be guided by these 75 rounded walls into the grooves of the corrugations and into alignment with the openings 20.

It is believed the operation will be clear from the foregoing description. In connecting the shell and the cap together the end of the shell may be inserted in the cap either when the locking ring 26 is in the locking position of Fig. 1 or when it is in the unlocking position of Figs. 4, 5 and 6. If it is in 80 the locking position of Fig. 1 the shell 12 is sufficiently yieldable so that the walls will be pressed inwardly by the operation of inserting the shell in the cap sufficiently to allow insertion of the shell and the passage of the 85 nibs 23 to the openings 20, at which time the walls of the shell will spring outwardly and then the ends of the nibs will engage the upper edges of these openings and lock the shell and the cap together. This yielding of 90 the walls of the shell is permitted by the notch 14 in the shell. This is a desirable feature if this shell is used on a lamp socket enclosed within a shade or globe where it is not readily accessible. It is also a convenient 95 way to secure the elements of the shell and cap together in ordinary usage as the ring may be easily shifted to the locking position while the cap is separate from the shell and then the cap and shell may be easily and 100 quickly locked together by merely inserting the end of the shell in the cap. It will, of course, however be obvious the end of the shell may be inserted in the cap when the ring is in the unlocked position and then the cap 105 and shell locked together by shifting the ring 26 to the position of Fig. 1. As indicated above this shifting movement will force the tongues 21 inwardly to position the nibs 23 in the securing position in the openings 20. 110 In separating the cap and shell all that is necessary is to first force the ring 26 to its upper or unlocked position, as shown in Figs. 4, 5 and 6 and then separate the cap and shell by merely pulling them apart. When the 115 locking ring is shifted to this unlocked position it releases the tongues 21, permitting them to move outwardly under their resilient action and withdraw the nibs 23 from the openings 20.

It is preferred to form the shell 12 with an outwardly extending bead 35 just below the edge of the locking ring 26 when it is in the locking position. This assists in strengthening and stiffening the walls of the shell, and 120

also covers the slight space between the edge of the ring and the outer wall of the shell giving a better appearance.

It will be apparent from the foregoing description that this construction provides a simple and effective means for locking the shell and cap together, and also one which gives a very strong and rigid connection between them sufficiently strong to carry relatively heavy weights, such as glass globes or shades. It will also be apparent the ring 26 positively holds the tongues 21 in the locking position so that there is very little liability of the shell and cap becoming accidentally detached. However, if it is desired to separate the cap and shell this may be easily accomplished by first moving the ring to the unlocking position, after which the cap and shell may be easily separated.

20 Having thus set forth the nature of my invention, what I claim is:

1. A casing for electrical devices comprising two telescoping sections, the inner section having a plurality of openings spaced from the end thereof, the outer section having a plurality of tongues having projections to extend into said openings to secure the sections together, and a locking ring embracing said outer section and slidably longitudinally thereof to and from a position over said tongues to lock them in holding position or to release them.

2. A casing for electrical devices comprising two telescoping sections, the inner section having a plurality of openings spaced from the end thereof, the outer section having a plurality of resilient tongues tending to move outwardly and having projections adapted to extend into said openings to secure the two sections together, and a ring on said outer section movable to a position to hold the tongues inwardly with the projections in said openings and to a position to allow said tongues to move outwardly to permit disconnection of the sections.

3. A casing for electrical devices comprising two telescoping sections, cooperating securing means on the two sections to secure them together, the securing means of one of the sections being mounted on resilient tongues tending to move away from the other section to separate said means, and movable means on one of the sections arranged in one position to hold the tongues in securing position and in another position to release them to allow them to move to an ineffective position.

4. A casing for electrical devices comprising telescoping sections, the inner section having a plurality of openings spaced from the end thereof, the outer section having a plurality of movable tongues having projections to extend into said openings to secure the sections together, and movable means on one of the sections arranged in one position to hold

the tongues in securing position and in another position to permit them to move to an ineffective position and allow separation of the sections.

5. A casing for electrical devices comprising telescoping sections, the inner section having a plurality of openings spaced from the end thereof, the outer section having a plurality of resilient tongues tending to move outwardly and carrying nibs to engage edges of the openings to secure the two sections together, a locking ring embracing the outer section and movable longitudinally thereon, cooperating shoulders on the outer section and the ring to limit the movements of the ring, and cooperating means on the ring and the tongues to hold the tongues inwardly to retain the nibs in the openings, said ring arranged to permit outward movement of the tongues to move the nibs from the openings when the ring is shifted to its other position.

6. A casing for electrical devices comprising telescoping shell and cap sections, said shell having a plurality of openings spaced inwardly from the end thereof, the cap being provided with slits from its free edge forming movable tongues, said tongues having nibs projecting inwardly in position to engage the edges of said openings to secure the shell and cap together, a locking ring embracing the cap and movable thereon, said ring arranged in one position to retain the nibs in the openings and in another position to permit them to move from the openings, and cooperating means on the cap and ring to limit the movements of the ring.

7. A casing for electrical devices comprising telescoping shell and cap sections, said shell having a plurality of openings spaced inward from the end thereof, said cap being provided with a plurality of resilient tongues having nibs to project into the openings and engage side edges thereof to secure the sections together, said cap being provided with a shoulder spaced inwardly from the end thereof and also stop means, a ring slidably longitudinally on the cap and having means cooperating with said shoulder and stop means to limit its movement in opposite directions, said ring in one position arranged to retain the nibs in the openings and in another position to permit them to move from the openings.

8. A casing for electrical devices comprising telescoping shell and cap sections, said shell having a plurality of openings spaced inward from the end thereof, said cap being provided with a plurality of resilient tongues having nibs to project into the openings and engage side edges thereof to secure the sections together, said cap being provided with a shoulder spaced inwardly from the end thereof and a bead adjacent the end, and a movable locking ring provided with means

cooperating with said shoulder to limit its movement in one direction and also provided with a bead cooperating with the bead on the cap to secure the ring in a given position, said ring when in the latter position being arranged to retain the tongues inwardly with their nibs in some of the openings in the shell.

9. A casing for electrical devices comprising telescoping shell and cap sections, said shell having a plurality of openings spaced inward from the end thereof, said cap being provided with a plurality of resilient tongues having nibs to project into the openings and engage side edges thereof to secure the sections together, said cap being provided with a shoulder spaced inwardly from the end thereof and a bead adjacent said end, said cap also having stop means between the shoulder and said first mentioned bead, a locking ring embracing the cap and movable longitudinally thereof, said ring being provided with a flange at one end and an inwardly extending bead at the other end cooperating respectively with said shoulder and the stop means on the cap to limit movements of the ring in opposite directions, said bead on the ring also arranged to cooperate with the first bead on the cap to retain the ring in one position, and said ring arranged when in the latter position to retain the tongues with their nibs in openings in the shell.

10. A casing for electrical devices comprising telescoping shell and cap sections, said shell being provided with a plurality of openings spaced inwardly from the end thereof, said cap being provided with a plurality of movable tongues carrying nibs adapted to project into said openings and engage side edges thereof to secure said sections together, and movable means on the cap arranged when in one position to retain the tongues with the nibs in said openings and when in another position to release said tongues.

11. A casing for electrical devices comprising telescoping shell and cap sections, said shell being provided with a plurality of openings spaced inwardly from the end thereof

and having its wall corrugated with the ribs thereof in alignment with the spaces between the openings to form guide grooves leading from the end of the shell to the openings, said cap being provided with a plurality of tongues having inwardly projecting nibs adapted to enter said openings and secure the sections together, and a locking ring embracing the cap and movable thereon, said ring arranged in one position to retain the tongues with said nibs in the openings and in another position to release said tongues.

12. A casing for electrical devices comprising telescoping shell and cap sections, said shell being of resilient sheet metal and provided with a plurality of openings spaced inwardly from the end thereof and also having a notch leading from said end to permit the walls of the shell to yield inwardly, resilient tongues on the cap tending to move outwardly and having inwardly extending nibs adapted to enter the openings in the shell to secure the sections together, and a locking ring embracing the cap and movable thereon, said ring arranged when in one position to retain the tongues in securing position and when in another position to permit said tongues to move outwardly and release the shell.

13. A casing for electrical devices comprising telescoping shell and cap sections, said shell being provided with a plurality of openings spaced inwardly from the end thereof, said cap being provided with a plurality of movable tongues carrying nibs adapted to project into said openings and engage side edges thereof to secure said sections together, inwardly projecting lugs on portions of the cap intermediate said tongues to enter the openings in the shell to prevent turning of the cap on the shell, and movable means on the cap arranged when in one position to retain the tongues with the nibs in said openings and when in another position to release said tongues.

In testimony whereof I affix my signature.

HARVEY HUBBELL, JR.
